CLAIM

The ornamental design for a golf-club caddy, as shown and described.

DESCRIPTION

FIG. 1 is a front left perspective of a golf-club caddy embodying my design;

FIG. 2 is an upper front perspective of the golf-club caddy shown in FIG. 1;

FIG. 3 is an upper rear perspective of the golf-club caddy shown in FIGS. 1 and 2;

FIG. 4 is a rear left perspective of the golf-club caddy shown in FIGS. 1-3;

FIG. 5 is a bottom view of the golf-club caddy shown in FIGS. 1-4;

FIG. 6 is a front right perspective of the golf-club caddy shown in FIGS. 1-5; and,

FIG. 7 is a right side elevation of the golf-club caddy shown in FIGS. 1-6, with the opposite side elevation being a mirror image thereof.
